COIN CONTROLLED APPARATUS

Morton L. Landreth, Elmhurst, Ill., assignor to
 Western Electric Company, Incorporated, New
 York, N. Y., a corporation of New York

Application July 21, 1936, Serial No. 91,636

8 Claims. (Cl. 194—16)

This invention relates to coin controlled apparatus, and more particularly to telephone coin collectors for use at pay stations.

This invention is particularly adaptable to the type of telephone coin collector disclosed in O. F. Forsberg U. S. Patent 1,043,219, issued November 5, 1912, and is directed to that portion of the mechanism by means of which a line circuit running to the central office is completed when a coin or token is deposited in the instrument. In this apparatus deposit of a coin or token is necessary before the substation can signal the central office and before the central office operator can actuate mechanisms in the instrument for disposing of the coin. Usually the deposited coin or token is caused to actuate a pivoted lever or trigger projecting into its path during its passage through the instrument. The movement of this trigger operates a mechanism which closes contacts forming a line switch to signal the central office and to allow an associated electromagnet to be controlled when desired by a distant telephone operator for collecting or refunding the deposited coins.

An object of this invention is to provide a coin controlled apparatus having a signalling mechanism of simplified construction and positive operation.

In one embodiment of this invention an improved coin indicating mechanism suitable for use in telephone coin collectors of the type disclosed in the above mentioned Forsberg patent is provided. To prevent fraudulent or faulty operation of the coin deposit signal, a counterweight for restoring the coin trigger after passage of a coin is mounted independently of the trigger and adapted to engage the trigger only against downward movement thereof. A line circuit for signalling the central office and operating the coin handling mechanism is controlled by means of a commutator segment mounted on the trigger and engaging two line contact springs. Normally the springs are tensioned against an insulated portion of the segment, and when the trigger is depressed by a deposited coin, a conducting portion of the segment bridges the springs and completes the circuit. A cam of rectangular section is mounted between the contact springs and connected to the armature of the electromagnet for releasing the springs from the commutator segment when the electromagnet is operated to collect or refund the deposited coins.

Other objects and advantages of the invention will be apparent from the following detailed

description taken in conjunction with the appended drawings, in which

Fig. 1 is a perspective view, partly in section, of an electromagnetically operated coin handling mechanism embodying the invention;

Fig. 2 is a plan view of a portion of the apparatus shown in Fig. 1;

Fig. 3 is a fragmentary sectional view of the apparatus shown in Fig. 2, taken along the line 3—3.

Fig. 4 is an enlarged perspective view of a portion of the apparatus shown in Fig. 1, and

Fig. 5 is a fragmentary sectional view of the apparatus shown in Fig. 4 taken on a vertical plane through the line 5—5.

As disclosed in the Forsberg patent a coin or token deposited in the apparatus is delivered under gravity into a container or hopper 10. Mounted adjacent to the hopper is an electromagnet 11 for operating coin directing mechanism within the hopper. The electromagnet comprises a pair of coils 12 wound on soft magnetic cores 13 and connected in series. An armature 14 is resiliently and pivotally mounted above and between the two coils at the end of a permanent magnet 15. Secured to the armature is an operating lever 16 which is connected to a movable coin directing vane (not shown) within the hopper through a link 17. When direct current is introduced to the coils by the central office operator, the cores are polarized in accordance with the direction of the current. They attract the polarized armature, causing it to rotate and swing the operating lever and thus move the coin directing vane in a selective direction to collect or refund the coin deposited in the hopper.

The coin signalling apparatus comprising this invention is mounted on top of the electromagnet. One element of this mechanism, a lever arm or trigger 18, is mounted pivotally on a horizontal shaft 19 secured to the electromagnet frame. The unsupported end of the trigger projects through a suitable opening 20 in the wall of the hopper into the path of the deposited coin, which causes the trigger to rotate on the shaft when its end is engaged by the passing coin.

A counterweight 21 is mounted pivotally on the horizontal shaft adjacent to and independently of the trigger. A lug or portion 22 projects from the counterweight for engaging the top of the trigger portion which extends beyond the supporting shaft on the side opposite the hopper. The counterweight operates to restore the trigger to its normal or elevated position and also to retain the trigger in normal position between 55

operations. The action of the counterweight is exerted against the trigger in only one direction through engagement between the lug projecting from the counterweight and the trigger. If the 5 instrument is jolted or jarred, as by a blow on the housing, when the trigger is in its normal position, the relatively heavy mass of the counterweight may be caused to rotate in a counterclockwise direction on its supporting shaft. However, 10 due to its individual mounting, the counterweight is free to move independently in this direction and, therefore, will not transmit its motion to the trigger, thus avoiding a false or purposely fraudulent operation of the signalling circuit under these circumstances. 15

The position of the trigger is employed to control the line circuit directly by contact between a commutator segment 23 secured to the trigger and a pair of line contact springs 24 and 25. 20 The commutator segment is fan-shaped and is fixedly joined to the trigger by means of a yoke member 26, causing it to rotate with the trigger on the horizontal shaft. The tensioned contact springs are elongated and supported at one end 25 with their free ends adjacent to the coin hopper and contacting with opposite faces of the commutator segment. This comprises a line switch in which the segment is rocked between the ends of the springs to control the flow of current in the 30 circuit in accordance with the position of the trigger.

The commutator segment includes an electrical conducting portion 27 and an insulated section 28. The segment body is made of metal having good 35 electrical conducting qualities and the insulated portion is made of rubber or plastic material moulded into recesses in the segment faces or varnish applied to the faces with a brush. The flow of current between the free ends of the 40 springs is controlled by the position of these insulated and conducting portions of the segment.

The ends of the two contact springs opposite the segment are secured to an extension of the 45 electromagnet frame 29 with screws 30 or other means, such as rivets. The springs are insulated from the electromagnet frame extension and from each other with suitable interposed material 31, such as fibre or rubber. At the mounting end, each spring is provided with a terminal 32 and 33. One terminal 32 is connected to the line circuit (not shown), and the other terminal 33 is connected to the winding of the electromagnet 50 coils through a cable 34. The line circuit is connected to the other terminal of the coil windings so that the operation of the electromagnet is dependent upon the position of the commutator segment. When the trigger is in its elevated or normal position the free ends of the 55 contact springs engage the insulated portion of the segment which prevents the passage of current between the springs and consequently the introduction of current to the electromagnet coils. When the trigger is depressed by a deposited coin the segment is rocked on its supporting shaft, causing the uninsulated portions of the segment to engage the spring ends. In this 60 position the current can flow between the spring ends through the conducting segment to complete the line circuit to the central office and to the coils which signals the central office operator and also permits the operator to actuate the electromagnet and refund or collect the deposited coin. 70

The ends of the tensioned springs engage the

segment with substantial pressure in order to insure satisfactory contact and consistent operation of the line circuit. This pressure also maintains the trigger in its normal position and prevents irregular rotation of the segment which might originate false signals. It also serves to hold the trigger in a depressed position after a coin has been deposited until the electromagnet is operated to dispose of the coin. In some cases a series of coins is deposited for a single 10 call, such as a toll call, and the springs hold the trigger out of the path of subsequent coins after it has been deflected by the first coin and until the electromagnet is actuated by the telephone operator. 15

In order to insure the prompt return of the trigger and segment to their normal positions, it is desirable to release the pressure between the springs and segment at the time the electro-magnet is energized. This is accomplished with a 20 cam member 35 of rectangular section located between the springs near their free ends. This cam is mounted on a vertical pin 36 which is bearinged in a bracket 37 on the electromagnet frame and has a portion bent at approximately 25 a right angle to engage a yoke 38 on the operating lever of the electromagnet. Normally the cam is located with its sides parallel to and out of engagement with the two line circuit springs. When the electromagnet is operated to collect 30 or refund the coin, the yoke on the armature engages the bent portion of the pin and rotates the cam approximately 45° which interposes the diagonal of the rectangular section of the cam between the springs and spreads and spreads them sufficiently to release the segment, thus permitting the counterweight to restore the segment and coin trigger arm to their normal positions. 35

When the cam is rotated on its axis the contact spring ends are forced from the segment, and the current through the springs is consequently interrupted before the motion of the armature and operating lever have been completed. To supply current to the coils to complete the armature movement a bridging contact spring 39 is provided. This bridging spring is secured to the same mounting as the contact springs and extends parallel and adjacent to one of the contact springs 25 with its free end 40 tensioned against the side of the rectangular cam. At its mounting end the bridging spring is connected electrically to the lead wire running to the winding of the electromagnet coil by means of a jumper wire 40 and insulated from the adjacent contact spring. The spacing between the free end of the bridging spring and the adjacent line contact spring is small and when the cam is rotated the bridging spring is forced into engagement with the contact spring before the circuit between the two contact springs and the commutator segment is opened. This establishes a circuit between the incoming line and the coils during the period that the two line springs are separated from the segment and permits the 55 coin disposing movement to be completed. 60

When the electromagnet is deenergized by the central office operator, the armature is restored to its horizontal position which causes the yoke on the operating lever to restore the cam. This 70 breaks the engagement between the bridging spring and the contact spring and permits the two line springs to contact the insulated portion of the commutator segment.

To control the range of movement of the arma- 75

ture, operating lever and associated apparatus, an arm 41 is secured to the operating lever for engaging a stop 42 mounted on the electromagnet frame. The extending arm engages the stop at 5 the termination of its selective movements to confine the motion of the operating lever within the range desired for the most satisfactory operation of the apparatus.

By providing for the direct operation of the 10 line circuit by the coin trigger, construction of the required mechanism is simplified, the number of component members minimized, and the possibility of faulty operation correspondingly reduced. The use of an independently mounted 15 counterweight also contributes to more satisfactory and consistent performance of the equipment.

Modifications of the specific structure described 20 herein are contemplated and it is to be understood that the scope of the invention is limited only by the appended claims.

What is claimed is:

1. In a coin actuated device, a container for receiving a deposited coin, a shaft external to 25 the container, a member mounted pivotally on the shaft and having a portion normally extending into the container for engaging the deposited coin to cause rotation of the member on the shaft in one direction, and a counterweight mounted freely 30 on the shaft, said counterweight having a portion for engaging the member to rotate the member in the opposite direction.

2. In a coin actuated device, a container for receiving a deposited coin, a shaft external to 35 the container, a pivotal arm on the shaft having an end portion normally projecting into the container to cause movement of the arm when a coin is deposited, a coin deposit signal switch on the shaft having a movable member secured to the 40 arm to cause rotation of the switch member in one direction when a coin is deposited, and a counterweight mounted freely on the shaft, said counterweight having a portion for engaging the arm and moving the arm and switch member in 45 the opposite direction to their normal positions.

3. In a coin controlled device, a container for receiving a deposited coin, a mechanism in the container for directing the coin, a coin signalling circuit, a pair of contact springs in the 50 circuit, a shaft, a commutator segment pivotally mounted on the shaft for normally contacting with the springs and controlling the flow of current in the signalling circuit, an arm projecting from the segment into the container for causing 55 movement of the segment in one direction to complete the circuit when a coin is deposited, a counterweight freely mounted on the shaft independently of the arm, said counterweight having a portion for engaging the arm and moving the 60 arm and segment in the opposite direction, and means responsive to the operation of the coin directing mechanism for removing the springs from the segment to permit the counterweight to restore the segment to normal when the coin 65 directing mechanism is operated.

4. In a coin controlled device, a container for receiving a deposited coin, a coin directing mechanism in the container, an electromagnet for operating the coin directing mechanism, an electrical circuit for supplying current to the electromagnet, a pair of tensioned contact springs in 70 the circuit, a rotatable segment having insulated

and conducting portions positioned between the springs with the insulated portion normally separating the springs, an arm extending from the segment into the container for rotating the segment when a coin is deposited and positioning the conducting portion of the segment between the springs, means for restoring the arm and segment to normal and a cam between the springs operated by the electromagnet for removing the springs from the segment when the electromagnet is energized to facilitate restoration of the arm and segment to normal. 5

5. In a coin collector, a hopper for receiving the deposited coin, a coin directing mechanism within the hopper, an electromagnet for operating the coin directing mechanism, an electrical circuit for indicating deposit of the coin, a switch in the circuit comprising a pair of contact springs normally tensioned against a commutator segment, and means operated by the electromagnet 10 for releasing the springs from the segment. 15

6. A telephone coin collector comprising a coin hopper, a coin diverting mechanism in the hopper, an electromagnet for operating the mechanism, an electrical circuit for supplying current 25 to the electromagnet, a switch in the circuit comprising a pair of contact springs normally tensioned against a commutator segment, and a cam between the springs and operated by the electromagnet for removing the springs from the segment 30 when the electromagnet is energized.

7. In a coin collector, a container for receiving a deposited coin, a coin directing mechanism within the container, an electrical circuit for indicating the coin deposit, a switch in the circuit 35 comprising a pair of contact springs normally tensioned against a commutator segment, and means responsive to the coin directing mechanism for releasing the springs from the segment when the coin directing mechanism is operated. 40

8. In a coin actuated apparatus, a container for receiving a deposited coin, a coin directing mechanism in the container, an electromagnet for operating the coin directing mechanism, an electrical circuit for supplying current to the electromagnet, a pair of tensioned contact springs in the circuit, a rotatable segment having insulated and conducting portions positioned between the springs with the insulated portion normally engaging the springs, an arm extending from the 50 segment into the container for rotating the segment when a coin is deposited for positioning the conducting portion of the segment between the springs and completing the circuit to the electromagnet, means for restoring the arm and segment 55 to normal, a cam between the springs operated by the electromagnet for spreading and removing the springs from the segment when the electromagnet is energized to facilitate restoration of the arm and segment to normal, and means for maintaining the circuit to the electromagnet during the movement of the cam comprising a bridging spring interposed between the cam and one of the contact springs, said bridging spring being normally insulated from the adjacent contact spring 60 and connected electrically to the opposite contact spring and being adapted to engage the adjacent spring during the major period of cam movement for maintaining the circuit to the electromagnet 65 during said period. 70
